DESIGN FOR A COMBINATION FOOT REST AND MAGAZINE RACK

Hans Magnus Juhlin, Houston, Tex.

Application July 28, 1941, Serial No. 102,521

Term of patent 7 years

To all whom it may concern:

Be it known that I, Hans Magnus Juhlin, a subject of the King of Sweden, residing at Houston, in the county of Harris and State of Texas, have invented a new, original, and ornamental Design for a Combination Foot Rest and Magazine Rack, of which the following is a specification, reference being had to the accompanying drawing, forming part thereof.

In the drawing the figure is a perspective view of the combination foot rest and magazine rack, showing my design.

I claim:

The ornamental design for a combination foot rest and magazine rack, as shown.

HANS MAGNUS JUHLIN.
